UNITED STATES PATENT OFFICE.

GEORGE ARTHUR GOODSON, OF MINNEAPOLIS, MINNESOTA, ASSIGNOR, BY MESNE ASSIGNMENTS, TO THE GOODSON TYPE CASTING AND SETTING MACHINE COMPANY, OF SAME PLACE.

COMPOSING-MACHINE FOR TYPE CASTING AND SETTING MACHINES.

SPECIFICATION forming part of Letters Patent No. 605,954, dated June 21, 1898.

Application filed January 25, 1897. Serial No. 620,612. (No model.)

To all whom it may concern:

Be it known that I, GEORGE ARTHUR GOODSON, a citizen of the Dominion of Canada, residing at Minneapolis, in the county of Hennepin and State of Minnesota, have invented 5 certain new and useful Improvements in Composing-Machines for Type Casting and Setting Machines; and I do hereby declare the following to be a full, clear, and exact description 10 of the invention, such as will enable others skilled in the art to which it appertains to make and use the same.

My invention has for its object to provide an improved strip-feeding device as part of 15 a perforator for preparing a representative punctured strip that is subsequently used to control the actions of a type casting and setting machine.

My present invention is especially designed 20 as an improvement over the feed devices disclosed in my pending application, Serial No. 493,115, filed December 8, 1893, entitled "Composing-machine for type casting and setting machines."

25 Although my invention is especially designed for the purpose above named, the same may be capable of use in other applications wherein the same functions are required.

To the ends above noted my invention consists 30 of the novel devices and combinations of devices hereinafter described; and defined in the claims.

The invention is illustrated in the accompanying drawings, wherein, like notations referring to like parts throughout the several 35 views—

Figure 1 is a front elevation of the upper portion of my so-called "graphotone" or "perforator," with some parts broken away, with 40 the movable member of the feed device in its uppermost or normal position as the same would appear after the strip had been fed. Fig. 2 is a plan view of the machine shown in Fig. 1. Fig. 3 is a perspective view of the 45 upper part of the machine, with some portions broken away, for better illustrating the construction, with the parts in the same position as shown in Fig. 1. Fig. 4 is a vertical section through the machine on the line $x^4 x^4$ 50 of Fig. 2, with some parts broken away and

others shown in elevation, the movable member of the feed device and the feed-hole punch and its plunger being shown in their lowermost position. Figs. 5^a and 5^b are respectively a rear elevation and a vertical section 55 showing the feed devices in their normal position or as shown in Figs. 1, 2, and 3. Figs. 6^a and 6^b are corresponding views in rear elevation and vertical section, showing the same parts as they would appear after the feed-hole plunger had made a part of its downward stroke, but before it had begun to move the feed-disk away from the strip. Figs. 7^a and 7^b are corresponding views in rear elevation and vertical section, showing the same 60 parts as they would appear at the limit of the punch-plunger's downward stroke; and Fig. 8 is a plan view of a part of a representative punctured strip as it is delivered from this machine. 70

As in my pending application above identified a narrow strip of paper a , similar to ticker-paper, is fed through a suitable strip-guide b and is there subject to a series of punches c for making holes therein to represent the line of composition, and to a punch f for making a series of holes along one margin of the strip, adapted for use in feeding the strip on the type casting and setting machine. The series of punches c are carried 75 by armature-levers c' , which are subject to springs c^2 and magnets c^3 . The magnets c^3 are energized through electrical connections (not shown) under the control of an ordinary type-writing machine. (Not shown.) The 80 feed-hole punch f is carried by a part f' , secured to a plunger-head f^2 . The plunger-head f^2 is connected by stem f^3 to an armature-lever f^4 , which is subject to a spring f^5 and a magnet f^6 . The tension of spring f^5 90 may be varied by collar f^7 , adjustably mounted on the guide-rod f^8 . The spring f^5 tends to throw the feed-hole-punch plunger into its uppermost position. The magnet f^6 is on a common return branch of the electric circuit 95 having connections to the magnets c^3 . Hence whenever any one of the magnets c^3 are energized the magnet f^6 is also energized. The plunger f^2 and the part f' carried thereby are suitably guided on a head-block or bracket 100

g, fixed to the main frame *g'* of the machine. The strip-guide *b* is also fixed to the block or bracket *g*. When passing through the guide *b*, the strip *a* is also subject to a feeding device, shown as composed of a resistance-roller *h* and a segmental friction-disk *h'*, between which the strip passes. The roller *h* is loosely or rotatively journaled to the frame-block *g*, with the roller working through a slot in the top plate of the strip-guide. The friction-disk *h'* works up through a slot in the bottom plate of said guide *b* and is pivoted to a carrier *h²*, which is mounted for vertical sliding movement on the block *g*, directly inward of the plunger *f²*. The journal of the disk *h'* extends through the head of the carrier *h²* and is provided with an arm *h³*, which plays between a pair of adjustable stops *h⁴*. The disk *h'* is subject to a light spring *h⁵*, shown as applied to the arm *h³*, which spring tends to rock the disk *h'* backward in the line of feed. The head of the disk carrier *h²* is shown as of segmental form in cross-section and is mounted for a limited up-and-down movement in a seat *h⁶*, cut in the block *g*. The downwardly-adjustable flat or body portion of the carrier *h²* works in a suitable vertical guideway cut in the block *g* and is provided with a pair of outturned lugs *h⁷*, which embrace the plunger-stem *f³* directly below the plunger *f²* and are subject to a spring *h⁸* of greater tension than the spring *h⁵*, which spring *h⁸* tends to hold the carrier *h²* at the limit of its upward movement. The spring *h⁵* is of such light tension, as compared with the spring *h⁸*, that the friction-disk *h'* will not be moved by said spring *h⁵* on the downward movement of the plunger *f²* and arm *f⁹* until after the carrier *h²* has been engaged and moved downward, so as to release the pressure on the strip *a*. The plunger *f²* receives a longer stroke than is permitted to the carrier *h²*. Near the limit of the downward stroke of the plunger *f²* the lower end of the same engages with the lugs *h⁷* on the carrier *h²* and moves the said carrier *h²* and the feed-disk *h'* downward therewith. The plunger *f²* also carries an upwardly-extended arm *f⁹*, which near the limit of the plunger's upward stroke is adapted to engage with an eccentrically-set pin *h⁹* on the feed-disk *h'* and thereby rock the said disk *h'* forward in the line of feed against the tension of the said disk's retracting-spring *h⁵*.

55 In virtue of the described construction it will thus be seen that the feed-disk *h'* is mounted for a rocking motion forward and backward in the line of the strip's travel and for sliding motion at right angles to the strip or the plane of its rocking motion. Otherwise stated, the disk *h'* rocks on its carrier *h²* and slides with the said carrier *h²*. Normally the strong spring *h⁸* holds the carrier *h²* at the limit of its upward movement with the feed-disk *h'* in frictional contact with the strip *a* in opposition to the resistance-roller *h* as a

stop. The upward movement of the plunger *f²* is limited by one of the adjustable stops *h⁴*, intercepting the arm *h³* on the journal of the feed-disk *h'*. The parts are shown in this normal position with the strip *a* between the roller *h* and the feed-disk *h'* in Fig. 1, and the parts are also so shown in their normal position, but without the strip, in Figs. 3, 5^a, and 5^b. The strip *a* is thus yieldingly clamped under considerable friction from the spring *h⁸*, between the said parts *h* and *h'*, during the time that the punch-plunger *f²* makes its downward or punching stroke or during the time that it moves from the position in Figs. 5^a and 5^b into the position shown in Figs. 6^a and 6^b. The plunger *f²* then strikes the lugs *h⁷* on the carrier *h²* and moves the said carrier downward therewith during the remainder of its stroke or while going from the position shown in Figs. 6^a and 6^b into the position shown in Figs. 7^a and 7^b; but as soon as the disk *h'* is pulled downward away from its strip-clamping position under the downward movement of the carrier *h²* the disk-retracting spring *h⁵* becomes instantly operative to rock the disk backward in the line of feed or from the position shown in Figs. 5^a and 5^b into the position shown in Figs. 7^a and 7^b. Then when the magnet *f⁶* is de-energized and the plunger *f²* is thrown upward by the spring *f⁵* the stiff spring *h⁸* will become operative to throw the carrier *h²* upward to its limit, so as to bring the disk *h'* into its normal or strip-clamping position against the resistance-roller *h* before the disk is rocked forward by the arm *f⁹* of the plunger. As the upstroke of the carrier *h²* is shorter than the upstroke of the plunger *f²*, the latter continues to move after the former stops. Under this continued upward movement of the plunger *f²* the arm *f⁹* carried thereby will strike the pin *h⁹* on the feed-disk *h'* and rock said feed-disk forward in the line of feed until intercepted by one of the stops *h⁴*, thereby moving or feeding the strip forward one step. This forward-rocking motion of the feed-disk *h'* does not occur until after the plunger *f²* has moved upward sufficiently far to carry the feed-hole punch *f* to a point above the strip *a*, thereby affording clearance for the free movement of the strip in the feeding action. The downward movement of the carrier *h²* is limited by the lower wall of the seat *h⁶*, in which the head of the carrier *h²* is mounted. The downward movement of the plunger *f²* is or may be limited by the magnet *f⁶*. The rocking motion of the feed-disk *h'* is limited by the adjustable stops *h⁴*, intercepting the arm *h³* on the disk's journal. These stops *h⁴* are formed by finely-threaded screw-bolts, and hence the feed-step may be graduated to a hair. The plunger *f²* and the carrier *h²* are held from outward displacement in respect to their guideways by cross-pieces *g²*, fixed to the back of the head-block *g*, which are spaced apart from each other to

afford the necessary clearance for the movement of the feed-plunger f^2 , as best shown in Fig. 3. The slide f' , which carries the feed-hole punch f , is turned inward and secured to the plunger f^2 between the cross-pieces g^2 , as clearly shown in Fig. 3. The vertical portion of the punch-carrying slide f' is suitably guided in the block g and is held from outward displacement by a suitable keeper g^3 .

With this improved construction it will be seen that a strip-feeding device is secured which operates on the strip solely by friction, but which is, nevertheless, reliable and true. It will also be noted that the feed-disk h' does not touch the strip during the return or backward rocking motion of said feed-disk. This prevents any displacement of the strip and also insures the alinement of the strip in its travel through the strip-guide. If the roller and the disk were in contact with each other during the return motion of the disk, the strip might be fed backward, and if a roller were substituted for the feed-disk h' , with a rolling motion in a constant direction, without clearance movement at right angles to the strip, the strip would not run true, but might buckle and sheer in its guideway. This feed mechanism herein shown is a radical improvement over the strip-penetrating or needle feed disclosed in my pending application hereinbefore identified. It was found in practice that the needle or strip-penetrating feed shown in my pending case would under some circumstances tear the strip or elongate the feed-holes. This was especially true if the action from the type-writer happened to be extremely rapid. With the friction-speed herein disclosed all these difficulties are entirely overcome, and it is found in practice that this feed mechanism will feed the strip with absolute precision without any injury thereto, no difference how rapid may be the action on the type-writer. Hence a perfect representative strip is produced from this machine, with all the holes therein accurately positioned, as is required for the control of the type casting and setting machine thereby. A specimen of this punctured strip is shown in Fig. 8, wherein the marginal holes directly on the cross-lines represent the feed-steps and subsequently coöperate with the feed devices on the type casting and setting machine, while the holes between the cross-lines on said strip represent the elements of the composition as produced by the punches c and coöperative with thrust-pins on the type casting and setting machine for controlling the actions of the same, as fully dis-

closed in my United States Patent No. 530,481 of date December 4, 1894.

For the purposes of this case it is not deemed necessary to give any further explanation as to the way in which the magnets c^3 are controlled from the type-writing machine in order that a bank of twenty punches c may make in the strip all the holes required to represent all the elements of any possible composition. These features are all fully set forth in my pending case above identified.

It will be understood, of course, that the invention herein disclosed is capable of modification in construction without departing from the spirit of the invention.

What I claim, and desire to secure by Letters Patent of the United States, is as follows:

1. In a strip-perforator, the combination with a resistance-roller, of a coöperating feed-disk mounted for rocking and sliding motion against retracting-springs, and a reciprocating punch-plunger cooperating with said springs to impart the strip-releasing and strip-feeding movements to said feed-disk, substantially as described.

2. In a strip-perforator, the combination with a strip-guide and resistance-roller, of a spring-held disk-carrier sliding substantially at right angles to the strip, a spring-held feed-disk pivoted to said carrier for rocking motion in the line of feed, and a reciprocating punch-plunger subject to a magnet and a spring, with said plunger arranged to slide said carrier against its retracting-spring and to rock said disk against its retracting-spring, at opposite limits of the plunger's stroke, substantially as and for the purposes set forth.

3. In a strip-perforator, the combination with a strip-guide, of the resistance-roller h , the rocking feed-disk h' , the sliding carrier h^2 for said disk, the stop-arm h^3 on the journal of said disk and working against one or more adjustable stops h^4 , the spring h^5 applied to said disk, the pin h^6 on said disk, the spring h^8 applied to said carrier, the punch-plunger f^2 mounted for a longer stroke than the carrier and engageable therewith at the opposite limits of the plunger's stroke, the arm f^9 on the plunger engageable with the pin h^6 on the disk, the magnet f^6 and the spring f^5 , all arranged and coöperating substantially as described.

In testimony whereof I affix my signature in presence of two witnesses.

GEORGE ARTHUR GOODSON.
